UNITED STATES PATENT OFFICE.

EDWARD W. N. BOOSEY, OF DETROIT, MICHIGAN.

TRENCH COVER AND FRAME.

Application filed June 26, 1925. Serial No. 39,795.

This invention relates to a trench cover and frame and the object of the invention is to provide a trench cover and frame adapted to support a series of pipe lines in a trench. 5 One of the particular objects of the invention is to provide a trench cover and frame which may be embedded in a floor over a trench so that the cover extends flush with the floor surface, the said frame carrying 10 supports for a series of pipe lines extending through the trench.

Another object of the invention is to provide a device of the character described in which the pipe lines may be readily inserted 15 in or removed from the trench and in which the frame members are spaced apart equally throughout their length.

A further object of the invention is to provide a trench frame which may be embedded in a concrete floor when the floor is laid, the trench frame being provided with recesses in which a series of transverse supporting rods may be readily positioned or removed. 20

25 A further object of the invention is to provide a rigid support for the trench cover.

These objects and the several novel features of the invention are hereinafter more fully described and claimed and the preferred form of construction by which these objects are attained is shown in the accompanying drawings in which—

30 Fig. 1 is a section through a floor and trench including a trench cover and frame embodying my invention.

Fig. 2 is an enlarged section through the frame members and trench cover.

Fig. 3 is an enlarged section taken on line 3—3 of Fig. 2.

40 Fig. 4 is a view taken from line 4—4 of Fig. 2.

Fig. 5 is a section taken on line 5—5 of Fig. 2.

45 As shown in Fig. 1 a trench 1 is dug in the ground and is walled up by means of the vertical side walls 2. As shown in Figs. 1 and 2 the frame members 3 are positioned on top of the walls 2 and each frame member 3 is provided with a longitudinal flange 4.

50 This flange 4 as shown in Fig. 4 is notched out at 5 continuously throughout its length but the flange 30 of the frame members is closed. The frame members 3 are of a height equal to the thickness of the usual concrete floor and the concrete floor

as shown in Figs. 1 and 2 is laid so as to extend flush with the upper edges 6 of the frame members 3. When the floor is laid the concrete is tamped through the notches 5 to fill the space 7 between the flanges 30 and 4 of the frame members and thus firmly embed the frame members in the concrete floor. Each frame member 3 as shown in Fig. 2 is provided with a longitudinal shoulder or ledge 8 on which the cover 9 is supported and as shown in Fig. 3 a recess 10 is provided at spaced intervals along the frame member 3 which opens through the shoulder 8. A loose spreader and hanger bar 11 is positioned in the recesses or notches 10 which are positioned opposite each other in the two frame members 3 and each member 11 forms a support for the hangers 12 which in turn support the pipe lines 13 in the trench. To hold the frame members 3 in correct 75 spaced relation each frame member 3 is provided with a notch 14 at spaced intervals which is recessed at 15 behind the notch and a bolt 16 is positioned in the opposite notches 14 and the enlarged recess 15 allow the nuts 17 on the bolts 16 to be positioned behind the notches 14. These nuts 17 may be tightened to support the frame members and hold them in correct spaced relation while being embedded in the concrete. The cover 9 as shown in Fig. 2 is provided with strengthening 80 ribs 18 and as shown in Fig. 5 each cover member 9 is provided with a flange 19 extending beneath and supporting the edge of the succeeding cover member 9. The frame members 3 may also be provided with overlapping ends so that a long trench frame 85 may be easily assembled in this manner. The cover members 9 are made of metal and extending flush with the surface of the concrete floor and may be readily removed to allow access to the pipe lines 13. After the cover members 9 have been removed the pipe lines may be readily removed by removing the bolts 16 and the hanger bars 11. It will 90 thus be seen that the pipe lines are always accessible for repairing by removal of the cover members 9.

95 From the foregoing description it becomes evident that the device is very simple and efficient in operation, will not easily get out of order, provides an arrangement whereby the pipe lines are always accessible and further provides a device which accomplishes the objects described. 100 105 110

Having thus fully described my invention, what I claim is—

1. In trench construction, frame members each adapted to form a side of the trench and to be embedded in concrete each frame having an inner closed flange and an outer notched flange at an angle one to the other, the frames having the upper edges thereof practically flush with the concrete surface and formed with a longitudinal shoulder, the said inner closed flanges each having a series of recesses extending to adjacent the bottom of the flanges and opening through the outer face thereof, a series of hanger bars in the recesses extending transversely of the trench and providing spacers, and bolts extending between the frame members adjacent the upper edge tieing the parts together.
2. In trench construction, a pair of frame members each adapted to form a side of the trench, each frame having an inner closed flange and an outer flange at an angle thereto, the said flanges being embedded in material of which the trench is formed with the upper edge practically flush with the surface thereof, the said upper edge of each frame having a longitudinal shoulder, a series of recesses in the inner closed flange opening through the outer face thereof and

extending to adjacent the bottom of the flange, a spacer bar extending between opposite recesses of the two frames providing a hanger, bolts extending between the flange adjacent the upper edge, and a cover member formed of sections with the opposite edges lying in the longitudinal shoulders of the frames.

3. A cover member for trenches extending beneath a concrete or like floor comprising the combination with the side walls of a trench, of frame members mounted on the upper surface of the walls and providing extensions thereof, each member being provided with a portion embedded in the concrete or plastic material of the floor, each frame having the upper edge practically flush with the floor surface and provided with a longitudinal shoulder and further having a series of recesses opening through the shoulder and inner face of the frame, spacer bars mounted in the recesses and providing supports for a pipe, and a cover formed of removable sections supported at opposite edges on the said longitudinal shoulders.

In testimony whereof I sign this specification.

EDWARD W. N. BOOSEY.
